CASE FOR A MEASURING INSTRUMENT

Robert H. Hose, Mountainside, N.J., and Arthur H. Lince, deceased, late of Morris Township, Morris County, N.J., by Henrietta A. Lince, executrix, Morris Township, Morris County, N.J., assignors to Bell Telephone Laboratories, Incorporated, Murray Hill, N.J., a corporation of New York

Filed June 22, 1961, Ser. No. 65,706

Term of patent of 14 years

(Cl. D26—1)

FIG. 1

FIG. 2

FIG. 3

FIG. 4

FIG. 1 is a perspective view of a case for a measuring instrument showing a new design;

FIG. 2 is a side elevation thereof, the opposite side having substantially the same appearance;

FIG. 3 is a top view thereof; and

FIG. 4 is an end view thereof.

The broken line disclosure in the drawing is for illustrative purposes only.

We claim:

The ornamental design of a case for a measuring instrument, substantially as shown and described.
